CIRCUIT CONTROLLING METHOD AND APPARATUS

Herbert C. Graves, Jr., East Bradford Township, Chester County, Pa., assignor to I-T-E Circuit Breaker Company, Philadelphia, Pa., a corporation of New Jersey

Application March 13, 1933, Serial No. 669,474

28 Claims. (Cl. 200—144)

My invention relates to methods and apparatus for interrupting electrical circuits, and more particularly to switches, circuit breakers and the like.

In accordance with one aspect of my invention, the arc incident to opening of a switch or circuit breaker is transferred from the switch or breaker contacts to an extinguishing chamber along a path which facilitates the transfer to the chamber and substantially prevents flow of arc gases of the chamber in reverse direction toward the contacts.

More specifically, the chamber is formed by stacked plates of insulating material having aligned openings forming the chamber, and which preferably, due to the shape of the openings, is provided with one or more convergences toward which the arc is forced, as by a magnetic field, to ensure extinction of the arc whether large or small; transfer of the arc is assisted by plates of metal interposed between and spacing the aforesaid plates of insulation, which metal plates also preclude flow of conductive gases from the chamber toward the switch contacts.

In some forms of my invention, the stack of plates may include plates which in whole or in part are of magnetic material, to increase the speed of movement of the arc toward the extinguishing chamber and/or to force it toward the aforesaid convergences of the chamber walls.

My invention also resides in the features of construction, combination and arrangement hereinafter described and claimed.

For an understanding of my invention, and for illustration of several modifications thereof, reference is to be had to the accompanying drawings, in which:

Fig. 1 is a side elevational view with parts in section (line 1—1 of Fig. 2) of a circuit breaker utilizing the invention.

Fig. 2 is a front elevational view, partly in section, of the structure shown in Fig. 1 (left half taken on line 2B—2B of Fig. 1; right half taken on line 2A—2A of Fig. 1).

Figs. 3—8 inclusive are detail views of parts shown in Figs. 1 and 2.

Fig. 3a is an explanatory figure.

Figs. 4a and 4b on reduced scale illustrate modifications of the plate structure shown in Fig. 4.

Fig. 9 diagrammatically illustrates the wiring of the circuit breaker of Figs. 1 and 2.

Fig. 10 illustrates another circuit breaker utilizing a modified type of extinguishing chamber.

Figs. 10a and 10b are detail views of modifica-

tions of the laminated arc-extinguishing chamber.

Figs. 11 to 13 are detail views of the plates or elements forming the chamber of Fig. 10.

Figs. 12a and 12b on reduced scale illustrate modifications of the plate structure shown in Fig. 12.

Fig. 14 illustrates in front elevation the relative positions of the plates of Figs. 11 to 13 when assembled.

Figs. 15 and 16 show composite elements for an arc-extinguishing chamber.

Fig. 17 is a side elevation of an assembly utilizing plates similar to Fig. 15.

Fig. 18 is a detail view of the thermal tripping element for the circuit breaker of Fig. 10.

Fig. 19 illustrates diagrammatically the wiring of the circuit breaker of Fig. 10.

Referring to Fig. 1, the movable contact 1 is held in closed circuit position to bridge the stationary contacts 2 and 3 by an over-travelled toggle comprising the link 4 connected at one end to the arm 5 of the handle member 6, and at the other end to the movable arm 7 carrying contact 1. The handle 6 may be lifted to break the toggle to permit a spring not shown to effect opening of contact 1, or the toggle may be broken in response to circuit conditions other than normal. For example, the tripping coil 8 upon occurrence of overload lifts the armature 9 which strikes the pin 10 to move the handle upwardly to open the breaker.

The arc incident to opening of the breaker is preferably drawn between the arcing tip 11 carried by arm 7 and the back arcing plate 12 which may, as shown, be a continuation of the upper contact 2. After the separation of the contacts, one terminal of the arc moves from the tip 11 to the front arcing plate 13 which is of the same polarity by virtue of the conductor D so that the arc extends between plates 12 and 13. This action is facilitated by the difference in impedance of the circuit through D and the circuit through the over-current device which produces a potential difference between the tip 11 and plate 13 causing the arc terminal to jump to the plate.

This conductor D has a further advantage in that the action described above decreases the time of current flow through the over-current device during the interruption of overloads, thus avoiding excessive stresses and heating.

Between the arcing plates are a series of apertured plates or laminations 14, such as shown in Fig. 3, arranged so that they form an arc-ex-

tinguishing chamber C. The plates are held in position by bolts 15, 16, and 17 which are insulated from the arcing plates 12 and 13. The upper central portions 18 of the plates 14 (Fig. 5 3) serve to reduce the cross-sectional area of the chamber by forming a ridge depending from the top of the chamber along its length; or otherwise expressed, the chamber converges at α and α' , and more particularly it is connected by the converging passages 19 and 19' to the aligned openings 20 and 21 of the plates which form discharge passages as hereinafter explained.

The arrangement insures contact of the arc with a large area of cooling surface for chilling the arc gases sufficiently to increase their dielectric strength above a critical value.

Moreover, the plates 14 may be made of insulating material which upon contact with an arc liberates a gas or gases which chill the arc and extinguish it and prevent it from re-forming; for example, they may be of fibre or equivalent, which release hydrogen and/or carbon dioxide when engaged by an arc, or they may be of other material coated or impregnated with gas-producing chemicals, for example, boric acid. In gen-

25 ing chemicals, for example, boric acid. In general, the gases best suited have high specific heat and low density as hydrogen, water vapor, etc. Certain chemicals release powerfully effective gases when subjected to an arc but lose their
30 dielectric strength at the time. With the stacked plate construction, it is possible to utilize such materials, as ammonium alum, and yet obtain proper dielectric strength for the stack by alternating plates containing the above type of chemicals with other plates which maintain their dielectric strength when subjected to an arc.
35

On each side of the stack of plates 14 are disposed the coils 22, 22a which are effective to move the arc upwardly into the chamber C and to force it into intimate contact with the converging wall structure of the chamber for chilling the arc gases. The coils 22, 22a are connected in parallel with each other and in series with the gap between plates 12, 13 (across the breaker terminals). As shown, the lower part of each coil induces a flux across the switch contacts and has a small radius of curvature at this point to form an intense field for effecting rapid separation of the arc from the contacts. While it is preferred to use a pair of coils, a single coil is effective in moving the arc upwardly into chamber C.

In an arc, a major portion of the current is conducted by a central core of gases at high temperature which is surrounded by gaseous cylinders whose temperatures are progressively lower outwardly from the core. The shell formed by the outer layers serves as an effective heat insulator for the core and permits a relatively low voltage to maintain an arc. So shielded, the arc core has a substantial thermal lag, the gases remaining at high temperature throughout the cycles of alteration of the current. In my device, by forcing the arc into the convergences a, a' of the wall structure, the outer gas layers are distorted, generally as shown in Fig. 3a, increasing the temperature gradient between the arc core and leading boundary of the arc and so increasing the rate of transfer of heat from the core to the chilling gases. Heat is also extracted from the arc in raising the surface of the insulation to gas-liberating temperature, driving off the gases and in raising their temperature, and also there is additional heat absorbed in the decomposition of some gases, for example, of carbon-dioxide to carbon monoxide and oxygen.

This device is effective in extinguishing large or small arcs because irrespective of the arc size it is forced into intimate contact with the quenching surfaces at a and a' . This causes an increase in the pressure in the chamber C which assists in extinguishing the arc. The mechanical strength of the plate structure and the design of the vents eliminate the possibility of dangerous pressures.

The arrangement is effective for interrupting 10 direct current arcs and is particularly suitable for alternating current.

The arc extinguishing structure shown in Fig. 1 is constructed of the plates 14 assembled on the bolts 15, 16, and 17; these plates are separated at the bottom by the metal plates 34 illustrated in Fig. 4, while the upper parts of the plates 14 are spaced by the washers 23 on the bolt 17. The metal plates 34 terminate between the upper and lower bolts so that recesses between 20 plates 14 exist on either side of the main chamber C and above the metal plates. These openings extend to the top of the structure forming vents for the discharge of gas.

The effectiveness of the arrangement is increased by this spacing of the plates 14, for in effect the cross-sectional area of the chamber C along its length varies abruptly from the width x , Fig. 3, to the width of the spacing between the walls 24 of the housings 25 for the arc transfer coils 22, 22a. As a result of the axial flow, the arc gases are violently agitated or mixed with the chilling gases which more readily penetrate into the arc core and chill it.

Turbulence splits the arc stream into threads 35 which become more numerous and tenuous, as the turbulence increases in violence. The thermal lag of the threads is insubstantial so that their temperature fluctuates widely, closely following the alternations in current. This 40 makes it easier to chill the arc gases, and thus to restore the dielectric strength of the path. The condition which prevents reforming of the arc after the current passes to zero is that the dielectric strength of the gases or rather the 45 breakdown voltage must increase more rapidly than the applied voltage. In operation, the action of the device is so rapid that the arc is usually extinguished at the first current zero after commencement of the arc or within a half 50 cycle.

The openings between the top edges of the spaced plates 14 may be closed, as by a cover plate overlying them. A space between the top of the plates and the bottom of the cover may 55 be advantageous. Again they may be left open, in which case, the length of the path to the top edge of the plate should be sufficiently long to prevent the gases issuing from the opening from being in such state that there is any likelihood of 60 re-establishment of the arc outside of the device.

The formation of the arc, its transfer, and the generation of gases by the arc follow in such rapid sequence as to be practically instantaneous. The generation of gases is so rapid that the extinguishment of the arc is accompanied by an explosion. To reduce the noise of the report, it is desirable to break the sound waves by the muffle plates 27. The openings 28 in the plates 27 are sufficiently large to offer insubstantial resistance to the flow of the gases from chamber C to atmosphere. As shown in Fig. 1, the muffle plates 27 may be supported by the bolt 17 which extends through the central openings 29 thereof. The plates 27 when of metal are insulated from 75

the bolt by tube 38 and are suitably spaced from each other by washers 31 of suitable insulating material.

To increase the volume of gases liberated, either or both of the arcing plates may be composed, at least in part, of a conductor, as carbon, which liberates chilling gases when heated by the arc. For example, the back plate 12, may be provided with a member 32 of carbon having an arcing tip 33 extending into the rear of chamber C.

The transfer of the arc from its source to the extinguishing chamber C is facilitated by making the plates 34 of conducting material, preferably brass, copper or a conducting alloy which gives off chilling gas at relatively low temperatures which, as shown in Fig. 1, are spaced from each other, as by the lower portions of the laminations 14. The arc travels upward toward the chamber in the form of a series of short arcs between the plates 34. Alternate plates 34 are disposed so that their upper inclined edges 35 point in one direction while the intermediate plates are arranged so that their upper inclined edges 35 extend in the other direction, Fig. 2.

As each arc section travels upwardly into chamber C, between adjacent plates 34, it is lengthened due to the divergence of the upper edges of the plates. The arc as a whole zig-zags between the upper diagonal edge of the plates, increasing in length as the upper ends of plates 34 are approached.

In lieu of plates of the shape shown in Fig. 4, there may be used plates 34a, Fig. 4a whose top edge is horizontal instead of sloping; or as shown by Fig. 4b, may be each replaced by two plates 34b, 34c which when in assembled position have their adjacent edges approaching each other in the direction of movement of the arc, leaving a narrow slot s at the top edges of the plate which may be horizontal, downwardly inclined from the slot, or any other desired shape.

The upwardly acting force of coils 22, 22a, the stretched condition of the arc, the generation of gas as the arc contacts with the edges of the laminations 14, the gas velocity along the axis of the chamber—all combine to free the arc from the plates and throw it against the central ridge at the top of the chamber for liberation of chilling gas as previously described.

The bolt 17 is preferably of magnetic material to increase the intensity of the flux at the ridge so that the arc is pressed hard against its sloping surface and forced into the converging slots 19, 19'. The intense field ensures intimate contact of the arc with the insulating material for enhanced chilling and for generation of large volumes of chilling gas. The arc gases and generated gases flow from the chamber at high velocity due to high pressures developed.

The spacing between plates 34 is so narrow with respect to the openings between the muffle plates 21 that a back pressure is built up which greatly restricts the downward flow of the gases. The chilling effect of these plates substantially prevents the flow of conductive gas to the breaker contacts. The major flow of the gases is along the main chamber C and the auxiliary passages 20, 21. The flow here is unrestricted and extremely high velocities are attained.

A preferred wiring arrangement for the breaker is shown in Fig. 9. The conductor D is connected as indicated so that the arc current does not traverse the tripping device 8 after transfer of the arc to plates 13 and 12.

Referring to Fig. 10 for illustration of another circuit breaker utilizing the invention, when the current through the tripping coil 76 is sufficiently high to actuate the armature 71 to tripping position, the movement of the latter breaks the toggle 78, 78a to allow the spring 79 to move the movable contact member 80 away from the stationary terminal 80—a and toward open-circuit position irrespective of whether handle 81 in the position shown is free or held manually. The outer terminal of the arc is transferred from the movable contact tip 82 to the front arcing plate 83, as in the modification of Fig. 1.

In this modification, the arc current flows through the bolts 84 through conductor 85 to the lower terminal of the circuit breaker to magnetize the iron laminations 86 (Fig. 13). The direction of current through the bolts is reversed with respect to the flow of current in the arc and the flux produced between the legs 87, 87 of the laminations moves the arc upwardly toward and into the extinguishing chamber C where it is forced against the convergence a of the insulation laminations 88 (Fig. 11) for chilling of the arc, generally as previously described. The gases discharge axially of the chamber through the opening 93 and laterally of the chamber through the vents v.

The copper laminations 89 (Fig. 12) serve to facilitate the upward motion of the arc and to restrict the passage of conductive gases downwardly toward the switch contacts. Also as in Fig. 1, adjacent copper laminations may have upper inclined surfaces directed in opposite directions to force the arc to zig-zag between them and increase in length as it is forced upwardly by the action of the iron laminations, or more specifically, by the interaction between the field of the arc and the field of the plates 86.

In lieu of the plates of Fig. 12 with inclined upper edges, there may be used plates 89—a, Fig. 12a, having top edges which are substantially horizontal, or preferably, each plate may be replaced by two plates 89b, 89c, Fig. 12b, which when assembled in the stack, have their adjacent edges converging upwardly and separated at the top by a gap s.

By way of example, in the above construction the copper, iron, and fibre laminations may each be about one-sixteenth inch in thickness affording for each group in the assembly about 25% iron, 50% fibre, and 25% copper with a vent v, at the top, of 25% as most clearly shown in Fig. 10a.

The velocity of the arc, the rate of discharge of the gases, and the life of the fibre, may be increased by utilizing the modification shown in Figs. 15 and 16. The lamination 90 (Fig. 15) is composite in that it is formed of two iron legs 91, 91 joined by a member 92 of copper, or brass. This lamination replaces the all copper or brass elements 89 (Fig. 12) and may be three-thirty-seconds of an inch thick. With fibre laminations 88a, about one-eighth inch in thickness, an iron lamination 86 of about one-sixteenth inch thickness and the aforesaid composite lamination, the ratio for each group of the assembly is about 44½% fibre, 55½% iron, and 33½% copper, with a vent of 33½%. The increase in iron is beneficial particularly for the smaller arcs.

The assembly as shown in Fig. 10b may also be built of composite laminations 93, Fig. 16, alternating with fibre laminations 88a in which case, all of the discharge will take place at the end of chamber C. The fibre laminations 88a

and the composite laminations 93 may be of the order of one-eighth inch in thickness. This composite lamination comprises an iron horse shoe with a non-magnetic plate 94 and an insulating lining 95 for the chamber C.

5 The tripping arrangement for the breaker is generally similar to that described and claimed in my application Serial No. 632,527 filed September 10, 1932. Briefly, the lower end of armature 77 normally engages a magnetic stop 36 which is an extension of the lower pole piece 38 of the tripping coil 76. Under normal conditions, the stop 36 restrains the armature from clockwise movement. Upon occurrence of very heavy 10 overloads, the attraction of pole 38 predominates, due to saturation of extension which is of reduced cross section, and instantaneous opening of the breaker is effected. For sustained lighter overloads, tripping is effected by the 15 U-shaped bimetallic strip 39 which bends downwardly so that the cam member 40 moves armature 77 from stop 36 to a position at which the attraction of pole 38 predominates whereupon armature 77 is magnetically actuated to tripping 20 position.

25 As shown most clearly in Fig. 19, conductor 85 connects the front arcing plate to the line side of the thermal strip 39 so that the arc current does not traverse it to cause burning particularly 30 at the bend of the U.

35 While several preferred arrangements have been illustrated, it is to be understood that my invention is not limited thereto but is co-extensive in scope with the appended claims.

3. What I claim is:

1. An arc extinguishing device comprising a substantially confined arc extinguishing chamber, and means including a plurality of spaced conductive plates extending adjacent the arc source 40 for transferring the arc to said plates and dividing it into a plurality of arcs extending therebetween, said conductive plates terminating in said chamber to facilitate the transfer of the arc thereto and terminal plates within said 45 chamber spaced for formation of at least one arc therebetween of substantially greater length than any one of said plurality of arcs.

2. An arc extinguishing device comprising a substantially confined arc extinguishing chamber having converging wall structure of insulating material, a plurality of conductive plates terminating in said chamber and extending in spaced relation adjacent the arc source, and magnetic means for effecting movement of the 50 arc along said plates into said chamber and toward the convergence of said wall structure thereof.

3. An arc extinguishing device comprising a substantially confined explosion chamber having converging wall structure laterally vented and of insulating material, a plurality of conductive plates terminating in said chamber and extending in spaced relation adjacent the arc source, and magnetic means for effecting movement of the arc along said plates into said chamber and toward said converging vented wall structure thereof.

4. An arc extinguishing device comprising alternate laminations of conductive material and insulating material, the laminations of insulating material forming a substantially confined explosion chamber and the laminations of conductive material terminating in said explosion chamber to facilitate the transfer of the arc thereto 70 from the arc source and forming restricted pas-

sages substantially preventing passage of conductive gases within the chamber to the arc source.

5. An arc extinguishing device for a switch having separable electrodes comprising a substantially confined explosion chamber whose interior is formed at least in part of insulating material and a plurality of conductive plates terminating in said chamber and extending in spaced relation adjacent the path of the arc between said switch electrodes for facilitating transfer of the arc to said chamber and for restricting passage of incandescent gases within said chamber toward said electrodes.

6. An arc extinguishing device for a switch comprising a substantially confined explosion chamber, electro-magnetic means for effecting transfer of the arc from the switch electrodes to said chamber, and means for facilitating transfer of the arc comprising a plurality of conductive plates terminating in said chamber and extending in spaced relation adjacent the path of the arc between said electrodes.

7. An arc extinguishing device comprising a coil whose axis is substantially normal to the arc, an explosion chamber whose axis is substantially parallel to the arc and which is substantially removed from the source of the arc, and a plurality of spaced conductive plates terminating in said chamber and extending substantially parallel to the axis of said coil adjacent to the arc source.

8. An arc extinguishing device comprising a substantially confined explosion chamber having internal wall structure of insulating material, plates in said chamber for forming the terminals of a single long arc, and a plurality of spaced conductive plates entering said chamber for transfer of the arc from its source into said chamber.

9. An arc extinguishing device for a switch having separable electrodes comprising a substantially confined explosion chamber having internal wall structure, a substantial portion of which is of insulating material; means for effecting transfer of the arc from said electrodes to said chamber, arcing terminals within said chamber for receiving said arc, at least a portion of one arcing terminal comprising carbon to liberate arc chilling gases in said explosion chamber when heated by the arc, and a vent for said chamber disposed for flow of gases axially of the arc between said arcing terminals within said chamber.

10. An arc extinguishing device comprising apertured laminations of insulating material aligned to form a substantially confined explosion chamber, plates of conductive material entering said chamber and spaced by said laminations, and a coil at the side of laminations and plates with the axis parallel to the planes thereof and normal to the arc for effecting transfer of the arc from its source to said plates and along said plates into said explosion chamber.

11. An arc extinguishing device comprising arcing plates, a stack of laminations between said plates having aligned openings forming a substantially confined arc quenching chamber, and muffle plates in the path of gases flowing from said chamber.

12. An arc extinguishing device comprising a plurality of composite laminations, each lamination having a part formed of insulating material and at least another part formed of conductive material, said laminations being provided with

openings disposed to form a substantially confined arc extinguishing chamber, terminals within the chamber for a single long arc, and spacers formed of insulating material interposed between adjacent laminations, said conductive portions of said laminations entering said chamber for transfer of the arc therebetween from its source to said terminals in said chamber.

13. An arc extinguishing device comprising a substantially confined arc-extinguishing chamber and a relatively narrow passage extending thereto, said chamber having internal wall structure of insulating material, and said passage having wall structure including magnetizable material for producing a magnetic field for moving an arc through said passage into said chamber.

14. An arc extinguishing device for a switch comprising a substantially confined explosion chamber, electro-magnetic means for effecting transfer of the arc from the switch electrodes to said chamber comprising a plurality of plates, a non-magnetic portion of each plate being conductive and terminating in said chamber, elements of insulating material associated with said plates and forming an insulating lining for said chamber.

15. A circuit-interrupting device comprising switch contacts, electro-responsive means for effecting separation of said contacts connected in series therewith, and arcing plates to which the arc between said contacts is transferred, connected in shunt to said contacts and said electro-responsive means.

16. A circuit-interrupting device comprising a fixed contact, an arcing plate connected thereto, a movable contact, electro-responsive means for effecting separation of said contacts having a terminal connected to said movable contact, a second arcing plate to which is transferred the arc terminal initially formed on the movable contact, and a connection from said second plate to another terminal of said electro-responsive means to exclude said movable contact and electro-responsive means from circuit upon said transfer of the arc.

17. A circuit-interrupting device comprising a fixed and movable contact between which an arc is drawn, a thermal-device traversed by the current traversing said contacts and adapted to effect their separation for excess magnitudes of said current, arcing plates, means to effect transfer of an arc from said contacts to said arcing plates, and connections excluding said thermal device from the circuit of the arc upon transfer of the arc to said arcing plates.

18. A circuit interrupting device comprising a substantially confined arc extinguishing chamber, a plurality of conductive laminations, the entrance to said chamber lying between said laminations and extending into said chamber for transfer from its source into said chamber of the arc as a plurality of short arcs, terminal plates within said chamber spaced one from the other and between which a plurality of the short arcs unite, means subjected to the heat of the said arcs for generating gas within said chamber, and a vent for said chamber of greater cross-sectional area than said entrance to insure exit of the gases in a direction away from the arc source.

19. A circuit-interrupting device comprising contacts between which an arc is drawn, arc terminal plates to which the arc is transferred, a stack of plates of insulating material between said terminal plates having substantially aligned

openings forming a substantially confined extinguishing chamber, means for facilitating transfer of the arc to said chamber and for preventing flow of conductive gases from said chamber toward said contacts comprising metal plates interposed between plates of said stack and terminating in said chamber, and means for accelerating the transfer of the arc and for pressing it against the wall structure of said chamber comprising plates of magnetizable material interposed between plates of said stack. 10

20. The method of extinguishing an arc which consists in dividing the arc into a plurality of short arcs, in a substantially confined chamber moving said short arcs at angles one to the other 15 and simultaneously lengthening each arc, in said chamber recombining a plurality of said arcs to form at least one relatively long arc, and by the arc heat generating arc-influencing gases.

21. A circuit-controlling device comprising separable contacts, a stack of laminations having aligned openings forming a substantially confined explosion chamber substantially removed from said contacts, arc terminal contacts at opposite ends of said chamber, a plurality of closely spaced 25 conductive plates included in said stack and terminating in said chamber to facilitate transfer of the arc to said chamber for re-formation as a single long arc therein between said terminal contacts and to restrict flow of conductive gases 30 from said chamber toward said separable contacts, means producing a flux for moving said arc against gas-releasing insulation in said chamber, and means for allowing escape of gases from said chamber in a direction away from said 35 contacts.

22. An arc-extinguishing device comprising slotted plates of conductive material having inclined upper edges, and means for holding said plates in a stack with their slots in alignment 40 and with the inclined upper edges alternately inclined in opposite directions.

23. An arc extinguishing device for a switch having contacts relatively movable to an open circuit position with formation of an arc therebetween, a substantially confined arc extinguishing chamber spaced from said contacts, means sub-dividing said arc for transferring the subdivisions thereof into said chamber, the heat of said arc generating gas pressure within said 50 chamber, insulating material lining at least a portion of said chamber and of a character for liberation of gases to augment said gas pressure, and means producing a high velocity gas flow within said chamber comprising a discharge vent 55 separate from the entrance to said chamber and through which said gases are expelled.

24. An arc-extinguishing device for a switch comprising a substantially confined elongated arc-extinguishing chamber provided with a restricted longitudinal openings adjacent to and closely spaced along the path of movement of the switch contacts, and means for transferring an arc from the switch contacts through said restricted openings to said chamber, and means in 60 said chamber for formation of an elongated arc therebetween, and a discharge vent at an end of said chamber for converting the pressure developed by said arc into a blast issuing therethrough in a direction away from said contacts. 65

25. An arc-extinguishing device for a circuit interrupter comprising means adjacent to the path of movement of the movable contact structure of the interrupter for receiving an arc therefrom and dividing it into a plurality of short 75

arcs with adjacent arcs at a substantial angle to each other and to the path of movement of said contact structure, and means for converting the pressure developed by said arc into a blast substantially normal to said short arcs to extinguish them.

10 26. An arc-extinguishing device for a circuit interrupter comprising a plurality of plates of conductive material adjacent to and closely spaced along the path of movement of the movable contact structure of the interrupter and normal thereto, said plates having their edges remote from said contact path alternately inclined in opposite directions, means for transferring an arc from the contact structure of the interrupter to said plates and across said plates to said inclined edges to cause it to assume a zigzag form, and means for converting the pressure developed by said arc into a blast substantially normal to said plates.

15 27. An arc extinguishing device for a switch comprising an explosion chamber having internal wall structure of insulating material which liberates chilling gas when engaged by an arc, a plurality of closely spaced conductive plates terminating in said chamber and extending adjacent the path of movement of movable contact

20 structure of the switch to receive the arc and transfer it away from said contact structure as a series of short arcs into said explosion chamber and contact plates spaced longitudinally of said chamber for the formation therebetween of a relatively long arc.

25 28. An arc extinguishing device comprising a plurality of substantially U-shaped laminations of magnetic material, non-magnetic conductive members bridging the legs of said laminations, a plurality of U-shaped laminations of insulating material alternating with said first-named laminations to form in conjunction therewith an elongated arc extinguishing chamber, said chamber having openings thereto extending between said conductive bridging members, elements formed of insulating material lining said first laminations opposite said bridging members, said magnetic laminations cooperating to move into said chamber a plurality of short arcs extending between said conductive members, means in said chamber for formation of a long arc therein, and a vent at one end of said chamber for converting the pressure developed by said arc into a blast substantially normal to said laminations.

HERBERT C. GRAVES, JR.
